UNITED STATES PATENT OFFICE.

OVANDO HOYT, OF OVANDO, MONTANA TERRITORY.

HAY UNLOADER AND STACKER.

SPECIFICATION forming part of Letters Patent No. 378,200, dated February 21, 1888.

Application filed August 18, 1887. Serial No. 247,275. (No model.)

To all whom it may concern:

Be it known that I, OVANDO HOYT, of 5
Ovando, in the county of Deer Lodge and Territory of Montana, have invented a new and Improved Hay Unloader and Stacker, of which the following is a full, clear, and exact description.

My invention relates to a device for unloading and stacking hay, and has for its object to 10 provide a means whereby the hay may be readily and quickly unloaded from the wagon without strain upon the team, and wherein, also, simultaneously with unloading, the hay may be stacked with little effort.

15 The invention consists in the construction and combination of the several parts, as will be hereinafter fully set forth, and pointed out in the claims.

Reference is to be had to the accompanying 20 drawings, forming a part of this specification, in which similar figures of reference indicate corresponding parts in all the views.

Figure 1 is a perspective view of the rack employed. Fig. 2 is a central transverse vertical section through the rack, illustrating the 25 sling in position thereon. Fig. 3 is a plan view of the sling. Fig. 4 is a plan view of a section of the hoist-rope, and Fig. 5 illustrates a rear view of a wagon with the sling in position.

30 In carrying out the invention the rack employed and illustrated in Figs. 1 and 2 is constructed of two horizontal base-beams, 1, having attached thereto upwardly, outwardly, and oppositely inclined end bars, 2 and 3, the end 35 bars, 2, being double and attached to each side of the base and the bars 3 to the upper edge of said base, projecting upward between the double bars, where the two end pieces are pinned together, partaking of the form of an

40 X, the double bars, however, being slightly longer than the single bars.

The base-beams 1 are united at one end by a horizontal brace-bar, 4, and the ends are further connected and the rack stiffened by the attachment of a second brace-bar, 5, to the outer edges of the single end bars, 3, above the base and below the center.

45 A longitudinal cross-bar, 6, is made to rest in the upper fork of the end bars, provided with a series of slats, 7, attached at right angles thereto from end to end, the said slats

being adapted to rest at their ends upon the brace-bar 5. The end bars at the top are provided with a finishing inclined cross-head, 8, 55 attached at one end between the double end bars, 2, and at the opposite end to the single bars 3.

Longitudinally the higher side of the rack a pin-carrying bar, 9, is secured to the upper 60 edge of the cross-heads 8, the pins 10 being secured at intervals in its outer side edge, as shown in Figs. 1 and 2. Longitudinally the lower side of the rack a bar, 11, is held by staples or otherwise in connection with the 65 cross-heads, and the said bar 11 is provided with a series of rails, 12, attached at right angles upon its inner side edge, extending over and beyond the pin-bar 9.

The slings 12^a, adapted to be used in the 70 wagon and in connection with the rack, consist of a series of lines, 13, preferably rope, of a length sufficient to lie upon the bed of the basket 14, carried by the wagon, as shown in Fig. 5, and when brought in contact with the 75 sides to extend over the same. The number of lines employed is governed by the length of the basket, and each line is secured at its ends to poles 15 and 16, adapted to hang longitudinally over the basket-sides, as shown in 80 Figs. 3 and 5. Outside the pole 15 loops 17 are formed of the bight portion of the outer ropes 13 by drawing each strand of said portion together about midway its length and fastening them by knotting, as illustrated in 85 Fig. 3.

The pole 16 has attached thereto near each end, preferably between the end and adjoining lines, 13, a short length of chain, 18, and to the inner link of each chain quite a length of rope, 90 19, is fastened, having secured at the other end rings 20.

At a convenient distance from the place selected for the stack a pole is held in a perpendicular position, from which are suspended 95 two or more pulleys, (not shown,) and over the pulleys a hoist-rope, 21, is passed, having one end fastened to a team of horses and the other end provided with a ring, 22, and pendent from said ring two flexible arms, 23, carrying hooks 24 at their ends, as illustrated in Fig. 4, and between the said arms a hook, 25, is also secured to the ring.

In operation, before proceeding to the field,

the sling is placed in the basket, as shown in Fig. 5, the poles hanging over the side, after which the hay is thrown in upon the slings until the load is made up. The rack having been placed where the stack is to be built, the wagon is driven up alongside the lower portion of the rack, with the pole 16 parallel and next thereto. The flexible arms 23 of the hoist-rope 21 are now thrown over the load, and by means of the hooks 24 are attached to the loops 17, the chains 18 having previously been hooked over one or more of the pins 10. The ropes 19, attached to the links, are now each fastened to the hook 25 upon the hoist by the engagement of the rings 20, and the sling, secured as in Fig. 2, is ready for manipulation. The team attached to the hoist-rope is now started, and the entire load is rolled from the basket upon the slatted table of the rack, consisting of the bar 11 and slats 12, and from thence down upon the ground. The ropes 19 being released from the hoist, the sling is readily withdrawn, the bar 6 and attached slats 7 preventing the hay from scattering beneath the rack.

The above operation is repeated until the stack has been built about as high as the rack. Then two slings are employed and the load delivered in two parts.

30 By the use of my invention hay may be handled much more readily than before and without much strain upon the team, as the load is not lifted from the wagon, but rolled off.

Having thus described my invention, what I claim as new, and desire to secure by Letters Patent, is—

1. A rack provided with crossed end bars, 2 and 3, horizontal bases 1, a longitudinal guide-beam, 5, attached at one side to the end bars, a longitudinal bar, 6, adapted to rest in the upper crotch of the end bars, having a series of slats, 7, attached at right angles thereto, adapted to rest upon the guide-beam 5, cross-

heads 8, uniting the end bars, a longitudinal pin-carrying bar, 9, secured near one end of 45 said cross-heads, and a bar, 11, secured upon said cross-heads having attached slats adapted to project beyond and rest upon the pin-carrying bar, substantially as and for the purpose herein set forth. 50

2. A sling for unloading hay, consisting of a series of parallel spaced lines, 13, attached at each end to poles 15 and 16, loops 17, secured to the pole 15 near each end, chains 18, secured to the said pole 16 near its ends, and 55 ropes 19, provided with rings 20, attached to said chains, substantially as and for the purpose herein set forth.

3. A sling for unloading hay, consisting of a series of parallel spaced lines, 13, poles 15 60 and 16, secured to said lines, loops 17, projecting from the outer side of said pole 15 at each end, aligning centrally the space intervening the outer lines, 13, and the next adjoining line, chains 18, secured to the outer 65 side of the pole 16, aligning the loops 17, and ropes 19, carrying rings 20, secured to said chains, substantially as and for the purpose herein set forth.

4. The combination, with the rack A, provided with the upper fixed longitudinal bar, 9, having attached pins 10, the parallel bar 11, provided with slats 12, the guide-bar 6 and attached slats 7, and the guide-bar 5, of the sling 12^a, consisting of the parallel spaced lines 75 13, attached poles 15 and 16, the loops 17, secured to the pole 15, chains 18, secured to the pole 16 in alignment with said loops, said chains adapted to engage the rack-pins 10, ropes 19, attached to said chains, carrying rings 80 20, and means for manipulating said sling upon the rack, substantially as set forth. 70
